UNITED STATES PATENT OFFICE.

JOSEPH F. PRITCHETT, OF COLUMBUS, GEORGIA, ASSIGNEE, BY DIRECT AND MESNE ASSIGNMENTS, OF ONE-FOURTH TO JOHN ALLEN JOHNSON, OF COLUMBUS, GEORGIA, ONE-FOURTH TO Q. T. FOSTER AND ONE-FOURTH TO F. A. PATRICK, BOTH OF COLUMBUS, GEORGIA.

STRINGER.

1,399,875.

Specification of Letters Patent. Patented Dec. 13, 1921.

Application filed December 31, 1920. Serial No. 434,317.

To all whom it may concern:

Be it known that I, JOSEPH F. PRITCHETT, a citizen of the United States, residing at Columbus, in the county of Muscogee and

5 State of Georgia, have invented a new and useful Stringer, of which the following is a specification.

I claim this stringer will save ninety-five per cent. of labor; at least twenty-five 10 per cent. of travelers, and will string four hundred travelers per minute.

This invention relates to machines for stringing travelers employed in connection with spinning frames in the manufacture of textiles.

The primary object of the invention is to provide a machine of this character which will automatically string the travelers, preparatory to placing the same in the spinning machine.

A further object of the invention is to provide a shaking table, designed to cause the travelers to be fed to their wires.

With the foregoing and other objects in view which will appear as the description proceeds, the invention resides in the combination and arrangement of parts and in the details of construction hereinafter described and claimed, it being understood 30 that changes in the precise embodiment of the invention herein disclosed, may be made within the scope of what is claimed, without departing from the spirit of the invention.

Referring to the drawings:—

35 Figure 1 illustrates a plan view of a machine constructed in accordance with the present invention.

Fig. 2 illustrates a sectional view taken on line 2—2 of Fig. 1.

40 Fig. 3 illustrates a front elevational view of the machine.

Referring to the drawings in detail, the machine includes a frame formed of the upper section 5 and lower section 6, the sections being supported by the legs 7 which are disposed at the respective corners of the sections.

Each section also includes side bars 9 and 10 respectively, which are supported in spaced relation with each other, as by means of the end bars 8.

Pivotedly supported between the side bars 9 of the upper section is a shaking table 11

which has a lower inclined wall 12, the table being supported however as by means of the 55 arms 13 which have connection with the side bars 9.

A plurality of openings 13' are formed in the inclined wall 12, at a point adjacent the forward end of the shaking table, which 60 openings are disposed in suitable spaced relation with each other and house the upper extremities of the rods 14, on which the travelers are positioned.

Secured to the outer walls of the shaking 65 table 11, are the depending arms 15 which are connected as by means of the rod 16 which rod 16 supports the heads 17, in which the rods 14 are supported, it being understood that the rods, due to the manner in 70 which they are supported, move with the shaking table 11.

A plurality of ribs 18 are supported within the shaking table, the ribs having inclined walls inclined toward the openings 13', to 75 direct the travelers to the openings when the shaking table, is in motion. Positioned within the side walls of the shaking table, is a partitioning member 19, which partitioning member contacts with the inner ends of 80 the ribs 18 to guard the inner ends of the ribs 18 and eliminate the possibility of the travelers passing to the rear of the shaking table, during the operation of the machine.

Formed in the partitioning member 19 at 85 points between adjacent ribs are openings 20, which openings permit the passage of the travelers from the main or body portion of the shaking table, to the channel ways 21, formed between the ribs, from where the 90 travelers pass through the openings 13, and onto the rods 14.

Operating above the frame is a box-like container 22, which has a hinged cover 23, the cover being of a width slightly less than 95 the width of the box to provide a passageway 24 between one edge of the cover and one wall of the box, the passageway being provided to permit travelers to fall from the container 22 and be deposited on the shaking 100 table.

The container is rotatably supported on the frame through the medium of the shaft 25 which is mounted in the bearings 26 and has one end thereof extending beyond the 105 side wall of the frame of the machine, where

the same has connection with a pulley 27 which receives rotary motion from the pulley 28, through the medium of the belt 29, which as shown operates over the pulleys 5 27 and 28 respectively.

This pulley 28 is secured to one extremity of the shaft 29' which shaft is mounted in the bearings 30 that are carried by the frame, on the opposite end of which shaft 29' is 10 disposed a pulley 31 that receives rotary motion from a suitable power device not shown. Disposed substantially intermediate the ends of the shaft 29 is a rotary member 32 which has a plurality of cams 33, formed 15 integral therewith, the cams being designed to contact with the lower front edge of the shaking table 12 to move the table 12 in one direction, as the member 32 is rotated, there being provided a coiled spring 34 which has 20 connection with the shaking table at one of its ends, and which also has connection with the frame of the machine as at 35, for moving the shaking table in the opposite direction. From the foregoing it is obvious that 25 as the machine is operated, the table 12 is reciprocated to agitate the travelers, to urge the same toward the forward portion of the machine.

Positioned within the frame adjacent to 30 the base thereof, is an apron 36 which extends directly under the shaking table at the forward portion thereof, so that any travelers which may pass through the openings 13 and which may not fall on the rods 14, 35 will be caught in the apron 36 where the same may be collected and returned to the shaking table for stringing.

It might be further stated however that 40 the heads 17, which are mounted on the shaft 16, are secured in their positions by means of the set screws 37, thereby permitting the heads to be adjusted longitudinally of their shaft. Associated with the set screw 37, is a set screw 38 which passes through a suitable threaded opening in the head associated therewith, where the same passes into a vertical opening formed in the head, which vertical opening receives the lower end of 45 its rod 14.

50 In the operation of the device, as the shaft 29' operates, the cams 33 move to oscillate the table 12, whereupon the travelers are moved downwardly, where the same fall through the openings 13', and over the rods 55 14, where the same are strung.

As the rods 14 become filled, they may be readily removed, whereupon the travelers may be put in operation.

Having thus described the invention, what 60 is claimed as new is:

1. A device for stringing travelers including a frame, a shaking table disposed above the frame, said shaking table having openings formed in the bottom wall thereof, traveler rods supported by the table and hav-

ing their upper ends disposed within the openings, said rods adapted to receive travelers from the shaking table, means for delivering the travelers to the shaking table, means for reciprocating the shaking table, 70 and means within the table for directing the travelers to the openings.

2. A device for stringing travelers including a frame, traveler rods disposed at one end of the frame, directly under the table, 75 said table having openings for delivering travelers to the rods, means for delivering travelers to the shaking table, and ribs disposed at one end of the shaking table for delivering travelers to the openings. 80

3. A device for stringing travelers including a frame, a shaking table adapted to oscillate in the frame, a partitioning member disposed within the shaking table, and providing a compartment adjacent to one end 85 thereof, ribs disposed within the compartment, said ribs having inclined edges, said table having openings, the ribs adapted to direct the travelers to the openings, means for delivering travelers to the table, and 90 traveler rods having one of their ends disposed within the openings to receive travelers.

4. A device for stringing travelers including a frame, a reciprocating table supported 95 by the frame, a rotary means for delivering travelers to the table, said table having openings, traveler rods having their upper ends disposed within the openings, means supported within the table for directing 100 travelers to the openings, and means for operating the table.

5. A device for stringing travelers including a frame, a shaking table operating in the frame, a shaft carried by the frame, and having a plurality of cams mounted thereon, 105 said cams adapted to contact with the shaking table for moving the same in one direction, resilient means for moving the table in the opposite direction, said table having 110 openings formed therein, traveler rods having one of their ends disposed within the openings for receiving travelers, means for delivering travelers to the table, and means for directing the travelers to the openings. 115

6. A device for stringing travelers including a frame, a shaking table carried by the frame, means for operating the table, means for dividing the table into compartments, ribs disposed in one of the compartments 120 for dividing the compartment into run-ways, said table having openings, a traveler rod disposed under each opening, said traveler rods adapted to receive travelers from the shaking table, and an apron supported under 125 the frame.

7. A device for stringing travelers including a frame, a shaking table supported by the frame, a rod supported under the frame and movable with the shaking table, ad- 130

justable heads on the rod, a removable traveler rod carried by each head, said shaking table having openings, one of the ends of the rods being disposed within the openings 5 to receive travelers therefrom, and rotary means for delivering travelers to the shaking table.

8. A device for stringing travelers including a frame, a reciprocating table supported 10 by the frame, a rod disposed under the table and movable therewith, a plurality of adjustable heads on the rod, said heads having openings, traveler rods disposed within the openings, means for securing the traveler 15 rods within the openings, said table having openings, the upper ends of the traveler rods being disposed in the openings to receive travelers therefrom, and means for delivering travelers from the table.

20 9. A device for stringing travelers including a frame, a shaking table carried by the frame, said table having a plurality of openings formed adjacent to one end thereof, a plurality of traveler rods, having their up- 25 per ends disposed within the openings to re-

ceive travelers, means carried by the table for delivering travelers to the openings, a rotary container supported by the frame and adapted to move over the shaking table for delivering travelers thereto, means for operating the shaking table, and means for rotating the container.

10. A device for stringing travelers including a frame, a shaking table supported by the frame, means disposed above the 35 frame for delivering travelers to the table, traveler rods disposed under the shaking table, said table having openings, said traveler rods having their upper ends disposed within the openings to receive travelers from 40 the shaking table, adjustable heads for supporting the traveler rods, and an apron disposed under the traveler rods.

In testimony that I claim the foregoing as my own, I have hereto affixed my signature 45 in the presence of two witnesses.
